UNITED STATES PATENT OFFICE

1,987,754

ELECTRIC DISCHARGE DEVICE

Richard M. Sherrill, Evanston, Ill., assignor to
 Central Scientific Company, a corporation of
 Illinois

Application March 26, 1932, Serial No. 601,399

1 Claim. (Cl. 176—42)

In scientific laboratories, it is the usual practice to use carbon arc lamps for point sources of intense light, and mercury vapor lamps for line sources.

5 As this invention concerns itself only with light sources that are enclosed within a glass vessel, the carbon arc lamp is not pertinent to this disclosure, unless housed within a glass tube or its equivalent, but as this is not customary, the 10 invention, for convenience, will be discussed as applied to a mercury vapor lamp.

Because of the intensity of the light emitted from a mercury vapor lamp, it is customary to provide a housing fitting over the lamp and 15 provided with suitable openings for directing a beam of light. This is necessary to protect other workers in the laboratory from being subjected to the intense light rays.

This invention seeks to eliminate the undesirable glare in an electric discharge device by providing means constituting a part of the device itself for limiting the emission of light waves to predetermined directions.

Further and other objects and advantages will 25 become apparent as the disclosure proceeds and the description is read in conjunction with the accompanying drawing, in which

Fig. 1 is a vertical, sectional view taken through a typical mercury vapor lamp to which the present 30 invention has been applied;

Fig. 2 is a front view thereof; and

Fig. 3 is a cross sectional view of the tubing used in the lamp.

While a mercury vapor lamp has been chosen 35 to illustrate an application of the present invention, it will be understood that the invention is equally useful in other electric discharge devices in which a source of light is enclosed within a transparent housing, and the claim, therefore, 40 is not to be construed as limited to the specific disclosure herein, except as may be required by express limitations and by the prior art.

In the illustrative embodiment of the invention, 45 the mercury vapor lamp, generally designated 10, comprises a vertical, tubular section or leg 11 having a laterally and downwardly extending branch 12 terminating at a point 13 below the lower extremity 14 of the leg 11. The lamp is 50 preferably made of high quality heat resistant glass in order to withstand the ravages of the electric arc.

Positive and negative electrodes 15 and 16 are sealed through the closed ends 13 and 14, respectively of the legs 12 and 11 and are adapted to

be connected to a suitable source of low voltage, high amperage electric current.

The upper portion of the tubular section 11 forms a condensing chamber 17 over the cathode, and through this chamber, a quantity of mercury, indicated at 18 and 19, is introduced. The lamp is then evacuated by means of a suitable vacuum pump, the seal off being indicated at 20.

To start an arc between the two pools of mercury 18 and 19, the lamp is tilted so that an excess of mercury will be contained in the leg 11 of the lamp. When the tube is righted, the excess will overflow the elbow 21, and strike an arc between the two pools of mercury 18 and 19, which is thereafter maintained by the ionized 15 mercury vapor.

The restrictions 22 and 23 in the legs 11 and 12 of the lamp are for the purpose of preventing the pools of mercury surrounding the electrodes from uncovering the latter when the tube is tilted to 20 strike an arc. In this way, the arc will always extend from mercury to mercury, and the electrodes are thereby protected.

Assuming that the mercury vapor lamp is to be used with apparatus requiring a beam of light 25 directed to the right (Figs. 1 and 3), this invention contemplates applying an opaque substance to the side and rear portions of the lamp to restrict emission of light to a forward direction. The opaque substance is preferably applied by 30 fusing it into the glass when the latter is in a molten state. The opaque substance may be any of the well known materials common in the art of glass manufacture for rendering glass imper- 35

In practice, a small quantity of transparent glass is consolidated with a larger quantity of opaque glass while the latter is being manipulated on the blow pipe, the result being to form opaque tubing having a transparent section running 40 longitudinally of the tubing.

The tubing could also be made by fusing an opaque substance in transparent glass tubing that has already been formed, or by any other suitable method.

The use of heavy cross hatching and stippling in the drawing is to indicate opaqueness.

The advantages of making the lamp from tubing such as has been described are apparent. There is no necessity for mounting the lamp in a 50 housing, or otherwise shielding the lamp, when such tubing is used. A saving in cost as well as convenience in handling are direct results of the invention.

The invention is obviously applicable to all 55

electric discharge devices of the type in which an electric current is conducted through a glass vessel between spaced electrodes for producing a source of light.

5 **What I claim therefore, is:**

In a mercury vapor lamp, a tubular glass envelope, a quantity of mercury in the envelope, spaced electrodes adapted to be connected to a

source of potential for producing an electrical discharge in said envelope of intense luminosity, said envelope being made of glass tubing that is opaque except for a longitudinal strip of transparent glass running substantially throughout its length.

5

RICHARD M. SHERRILL.
